Des. 67,613

UNITED STATES PATENT OFFICE.

STEPHEN MORRIS, OF NEW YORK, N. Y.

DESIGN FOR A BABY-CARRIAGE HOOD.

Application filed April 24, 1925. Serial No. 13,214. Term of patent 7 years.

To all whom it may concern:

Be it known that I, STEPHEN MORRIS, a citizen of the United States of America, residing at New York, in the county of Bronx and State of New York, have invented a new, original, and ornamental Design for a Baby-Carriage Hood, of which the following is a specification, reference being had to the accompanying drawing, forming a part thereof.

The figure is a perspective view showing my new, original and ornamental design for a baby carriage hood.

I claim:

The ornamental design for a baby carriage hood as shown.

STEPHEN MORRIS.

Witnesses:

JOHN GILLIGAN,
DANIEL J. DUNN.
